G. A. WATKINS, OF PROCTORSVILLE, VERMONT.

Letters Patent No. 64,727, dated May 14, 1867.

IMPROVED SEAT-FRAME FOR CHAIRS.

The Schedule referred to in these Letters Patent and making part of the same.

TO ALL WHOM IT MAY CONCERN:

Be it known that I, G. A. WATKINS, of Proctorsville, Windsor county, Vermont, have invented a new and useful improvement in Seats for Chairs; and I do hereby declare that the following is a full, clear, and exact description thereof, which will enable others skilled in the art to make and use the same, reference being had to the accompanying drawings, forming part of this specification.

The invention consists in the use of metallic corner pieces to the corners of the chair-seat frame, of suitable construction and form to receive and hold the legs to the chair, whether the front or rear legs, as will be herein-after more fully described. In the accompanying plate of drawings my improvements in frames for chair seats are illustrated—

Figure 1 being a plan view of the under side of the chair-frame, showing it broken out, and in partial horizontal section upon one side.

Figure 2, a transverse section, taken in the plane of the line *x x*, fig. 1; and

Figure 3, an edge view of one of the corner pieces.

Similar letters of reference indicate corresponding parts.

A, in the drawings, represents the chair-seat frame, which frame is made four-sided, but of a greater width at its front, *B*, than at its rear side, *C*, *D*, *E*, *F*, and *G* being the several strips or bars of wood forming the seat-frame. The several strips *D*, etc., at their ends are cut on a mitre or angle, so that, when put together, they will form the requisite size and shape of seat-frame, and make perfect corners. At each end of the strips *D*, etc., a groove is made or cut, of suitable shape and size to receive the flat key-pins *H* that are driven into them at the several corners to the seat-frame, as plainly shown in the drawing, by which key-pins the corners are made strong, rigid, firm, and stiff, as is obvious without any further explanation. *I*, the metallic corner pieces for the chair-seat frame, which corner pieces, according to their attachment to the chair seat, whether at the front or rear side, are constructed in the one case with a hollow socket, *J*, for the edges to be inserted in, either by screwing or in any other proper manner, and in the other or latter case with an extension corner piece, *K*, forming a nut, into which a bolt or screw can be screwed for fastening the rear legs to the edge of the chair-frame when such legs extend upward, forming the supports for the back-frame to the chair. In lieu of using the flat-shaped key-pins, and grooving the corners of the chair-frame, as has been described, dowel-pins may be employed for uniting the corners together, the present invention, in this particular, consisting in cutting the strips or bars at their ends, where to be jointed together, upon an angle or mitre, and securing them together by key or dowel-pins, or any equivalents therefor, applied substantially as described.

I claim as new, and desire to secure by Letters Patent—

Securing the legs to the seat of the chair by means of the metallic corner pieces *I*, provided with the perforated extension-plate *K*, bent at right angles thereto, and forming nuts to receive a bolt passing through the leg of the chair, substantially as herein shown and described.

The above specification of my invention signed by me this 14th day of February, 1867.

G. A. WATKINS.
